UNITED STATES PATENT OFFICE.

CHARLES H. HISER, OF SPRINGFIELD, OHIO, ASSIGNOR TO THE SPRINGFIELD METALLIC CASKET COMPANY, OF SPRINGFIELD, OHIO, A CORPORATION OF OHIO.

HERMETICALLY-SEALED COFFIN.

SPECIFICATION forming part of Letters Patent No. 790,729, dated May 23, 1905.

Application filed April 20, 1904, Serial No. 204,001.

To all whom it may concern:

Be it known that I, CHARLES H. HISER, a citizen of the United States, residing at Springfield, in the county of Clark and State of Ohio, have invented a certain new and useful Improvement in Hermetically-Sealed Coffins, of which the following is a specification.

My invention relates to the class of undertaking specialties, and particularly to sealing-packages for undertakers' use, and is especially adapted to be used in connection with devices shown in my application, Serial No. 201,854, filed April 6, 1904.

In the course of professional work the undertaker frequently finds it desirable to hermetically seal coffins, caskets, or grave-vaults, air-hardening cement being used. As generally employed the sealing-cement has to be mixed on the ground and used rapidly, because it begins to set as soon as applied.

The object of my invention is to arrange a sealing device so that it may be readily and safely transported without deleterious effects and after being transported can be combined with the flanges of the top and bottom portions of the coffin, so as to constitute an improved hermetically-sealed coffin.

To this end my invention consists of the construction and combination of parts and substances or their equivalents hereinafter described, and set forth in the claim.

In the drawings, Figure 1 is a sectional perspective view of a portion of the sealing-flanges of a grave-vault with my sealing-package in position and prepared for use. Fig. 2 is a perspective view of the sealing-package, partly broken away. Fig. 3 is a sectional view through the exterior casing of the package.

Like parts are represented by similar characters of reference in the several views.

In the drawings, *a* represents the sealing-channel about the lower part of the grave-vault, casket, or coffin, and *a'* the sealing-channel of the lid, which is adapted to inclose the lower channel.

The sealing material *b* is an air-hardening cement, which under ordinary circumstances

is not only disagreeable and inconvenient to handle, but as usually employed must be mixed at the grave and applied by workmen under circumstances and conditions which make it difficult to secure the proper sealing. To mold this sealing material *b* to a shape and size suitable for use in the sealing-channel *a* and to cause it to retain this form and to place it in a condition more convenient for handling, I inclose the sealing material in an extended bag or tube *b'*, formed from thin paper of durable texture, but adapted to be readily severed, so as to permit it to exert its sealing effect without removing the covering. It has been found that the most practical way to accomplish this is to first form the tube *b'* and then fill it in the manner of and by means similar to that employed for stuffing sausages. After the tube *b'*, which is formed with the closed end *b*², is filled it is closed with a cap *b*³. This, however, might be accomplished by folding in the end of the tube or otherwise, and the entire tube, with its contents, is coated with an air-proofing substance *b*⁴, Fig. 3, preferably by dipping the entire tube in melted paraffin.

To afford protection in shipping and as an additional security against deterioration, the air-proofed tube and contents are inclosed in a tubular casing *c*, preferably of pulp or straw-board, with closed ends, which in turn is treated to a coat *c'* of air-proofing substance in a similar manner to the tube *b'*.

When the sealing-package is to be used, it is only necessary to remove the tube *b'* from the casing *c*, lay it in the sealing-channel of the grave-vault, coffin, or casket, and with a knife or other sharp instrument slit the tube *b'* lengthwise in one or more places, so as to expose the sealing material, as shown in Fig. 1. When the lid is placed in proper position with the inner channel formed in the lid engaging the surface of the cement, the cement is readily pressed into proper shape to form an air-tight joint. It will thus be seen that I provide a coffin-sealing device molded and retained in proper shape and free from the deteriorating effects of the air and adapted

when placed in combination with the receptacle and the lid for the receptacle to be forced to conform to the shape of the inner channel formed thereby and to form in connection therewith an air-tight joint.

Having thus described my invention, I claim—

The combination of a receptacle, comprising a bottom portion and the lid adapted to fit over the bottom portion, an air-proof tube 10 of sealing material retained in shape to fit within said bottom portion and coöperating

with the lid portion whereby after the tube is severed the particles of sealing material within said tube will be displaced by said lid, and 15 the shape be changed so as to form an air-tight joint.

In testimony whereof I have hereunto set my hand this 16th day of April, A. D. 1904.

CHARLES H. HISER.
